US0D1076958S

(12) **United States Design Patent** (10) **Patent No.:** **US D1,076,958 S**
(45) **Date of Patent:** **** May 27, 2025**

(54) **ELECTRONIC DEVICE DISPLAY SCREEN OR PORTION THEREOF WITH GRAPHICAL USER INTERFACE**

(71) Applicant: **Truist Bank**, Charlotte, NC (US)

(72) Inventors: **James Harrison Creager**, Raleigh, NC (US); **Reinaldo Gamaliel Rivera Colon**, Raleigh, NC (US)

(73) Assignee: **Truist Bank**, Charlotte, NC (US)

(**) Term: **15 Years**

(21) Appl. No.: **29/962,678**

(22) Filed: **Sep. 12, 2024**

(57) **CLAIM**

The ornamental design for an electronic device display screen or portion thereof with graphical user interface, as shown and described.

DESCRIPTION

The sole FIGURE is a front view of an electronic device display screen or portion thereof with graphical user interface.

The outermost broken lines illustrating an electronic device display screen or portion thereof with graphical user interface form no part of the claimed design. The remaining broken lines illustrating portions of the graphical user interface form no part of the claimed design.

1 Claim, 1 Drawing Sheet
